United States Patent [19]
Aoyama

[11] **Patent Number:** **Des. 282,664**
[45] **Date of Patent:** ** Feb. 18, 1986

[54] **MICROPROCESSOR**

[75] Inventor: Nobuhisa Aoyama, Yokohama, Japan
[73] Assignee: Tokyo Shibaura Denki Kabushiki Kaisha, Kawasaki, Japan

[**] Term: 14 Years

[21] Appl. No.: 471,318

[22] Filed: Mar. 2, 1983

[30] **Foreign Application Priority Data**

Sep. 3, 1982 [JP] Japan 57-39997
[52] U.S. Cl. D14/100; D14/109
[58] Field of Search D14/100, 109; 360/97,
360/98, 99

[57] **CLAIM**

The ornamental design for microprocessor, substantially as shown.

DESCRIPTION

FIG. 1 is a front, top and right side perspective view of a microprocessor showing my new design;
FIG. 2 is a front elevational view thereof;
FIG. 3 is a right side elevational view thereof;
FIG. 4 is a top plan view thereof;
FIG. 5 is a left side elevational view thereof; and
FIG. 6 is a rear elevational view thereof.

FIG. 1

FIG. 2

FIG. 3

FIG. 4

FIG. 5

FIG. 6
